UNITED STATES PATENT OFFICE.

EMMETT QUINN, OF WASHINGTON, DISTRICT OF COLUMBIA.

IMPROVEMENT IN STORING PETROLEUM, &c.

Specification forming part of Letters Patent No. 58,475, dated October 2, 1866.

To all whom it may concern:

Be it known that I, EMMETT QUINN, of Washington, District of Columbia, have invented a new and Improved Device for Storing Petroleum and other Oils; and I do hereby declare the following to be a full and exact description thereof, reference being had to the accompanying drawings, and to the letters of reference marked thereon.

This device is intended to be moored in a dock, alongside a wharf or pier, or between boats or scows; and it consists of a platform or raft, hollow or solid, and depending on the specific gravity of its material for buoyancy. On this platform is built a frame or crib, having as many openings as are necessary on one or more sides, extending from the bottom to the top, and which are closed, as the cargo fills in and sinks, by means of movable bars or slats. The freight or cargo, being of nearly the same specific gravity as water, will require but little adjustment to maintain the proper level of the crib and cargo, and this is readily accomplished by increasing or diminishing the weight of the counter-balances provided for that purpose, or by means of capstan or windlass. When loading or unloading, the top course of barrels is kept above water a convenient distance. At other times the whole cargo is submerged, an old chain cable or other weight being laid on top of the last courses. The crib is surrounded on the two sides by the boats or scows, on the other sides or ends by wide planks set edgewise in the water, and connected by elastic joints to the sides of the boats. By this means whatever leakage there may be will accumulate above the cargo, and can easily be collected from the surface of the water, instead of being lost, as it is in the present method of storage, besides being the principal source of danger in case of fire.

A represents the floating platform, support-

ing the framing or crib B, and held in place by boats or scows C, or by being alongside of a wharf, whose top may be represented by the red line *x x*.

The dotted lines D D at each end of the crib represent the planks connecting the boats.

E E represent weights connected to the platform at *e*, by means of the chain or wire rope *b*, passing over the pulley *c*, supported by the stud or post *a* on the inside of the boat. These weights are cast-iron boxes, and by increasing or diminishing their contents, the crib and platform, with its cargo, is raised or lowered.

F F &c. represent the cargo, the upper layer being beneath the level of the water *y y*.

The red dotted circles F' F' represent the position of the top course relative to the water-level when loading or unloading the cargo.

The advantages of this mode of storing oil are obvious. It is perfectly safe from fire, instead of being the main cause of fire, as in other methods of storing. It is economical, as it tends to prevent and saves what little there may be of leakage. No evaporation and, consequently, no accumulation of explosive gases. The barrels will be kept clean, and are, therefore, less liable to accident from fire in transportation after having been so stored, and are more easily handled; and lastly, can be made to occupy less valuable room than when on a wharf or pier or in a warehouse.

Having thus described my invention, what I claim as new, and desire to secure by Letters Patent, is—

A dock or crib, with its appurtenances, in which to store petroleum or other oils in barrels or casks, constructed and used in a manner substantially as described.

EMMETT QUINN.
